UNITED STATES PATENT OFFICE.

WILLIAM QUAIL, OF BROOKLYN, NEW YORK.

PROOF-PRESS.

SPECIFICATION forming part of Letters Patent No. 238,525, dated March 8, 1881.

Application filed January 11, 1881. (No model.)

To all whom it may concern:

Be it known that I, WILLIAM QUAIL, of Brooklyn, Kings county, New York, have invented, made, and applied to use Improvements in the Construction of Proof-Presses for Use by Printers; and I do hereby declare that the following is a full, clear, and correct description of my invention, reference being had to the accompanying drawings, making part of 5 this specification, and to the letters of reference marked thereon, in which—

Figure 1 is a front elevation of my improved proof-press. Fig. 2 is an end sectional view of the same. Fig. 3 is a view of one of the circular plates of metal F. Fig. 4 is a view of one 15 of the boxes E and its regulating-screw I.

In the drawings like parts of the invention are designated by the same letters of reference.

The nature of the present invention consists 20 in certain improvements in the construction of proof-presses for use by printers, as more fully hereinafter set forth, the object of the invention being the production of a proof-press applicable to the taking of proofs from types secured in 25 a chase or locked up upon a galley, which press shall be easily operated, and can be afforded at a low cost to the consumer.

To enable those skilled in the art to make 30 and use my invention, I will describe its construction and operation.

A shows a frame provided with a handle, B, and sides C, having at their bases the wheels D. The sides C are secured to the frame A by screws or in any convenient way, and are slot- 35 ted, as at e, to receive the boxes E, provided with central openings, within which are inserted the circular plates of metal F, upon the inner side of each of which is secured eccentrically a pin, f, and upon the outer side or face 40 a crank-arm, g, by which the circular plate of metal F may be turned as desired, changing the position of the eccentric-pin f.

G shows a roller formed of vulcanized rubber or like material and supported upon a 45 shaft, H. This shaft is provided at each end with a central opening, within which the eccentric-pins f have a bearing, so that as the position of these eccentrics is changed the shaft H and roller G may be raised or lowered, as 50 desired.

I are thumb-screws, passed through the upper portions of the side C, and engaging with screw-threaded openings in the boxes E, by which the position of the boxes E is regulated; and J are set-screws placed above and below the boxes E, upon which they have a bearing to retain the boxes in any desired position in which they may be placed.

Such being the construction, the operation is as follows: The press is intended to enable 60 the printer to take proofs from a form of types placed upon a galley or secured in a chase. As the type secured upon a galley will stand higher than if secured in a chase, means are provided for raising the roller G, secured upon 65 the shaft H, consisting of the circular plates of metal F, provided with the eccentric-pins f, having their bearings in a shaft, H. When a proof is to be taken from a form secured in a chase the crank-arms g, attached upon the 70 faces of the circular plates of metal F, are turned up, so that the eccentric-pins f, upon the opposite sides of the circular plates of metal F, are lowered, lowering the roller G held upon the shaft H; and when a proof is to 75 be taken from a galley the crank-arms g are turned down, by which the eccentric-pins f are raised, raising the roller G secured upon the shaft H. When desired the position of the boxes E is varied by manipulating the thumb-screws 80 I, and when adjusted to any particular position are held in that position by the set-screws J, placed above and below them. The roller G upon the shaft H having been raised or lowered, as the character of the proof to be taken 85 requires, the form is inked, a sheet of paper laid upon the same, and the press passed over the paper, the roller G bearing upon the same sufficiently to cause an impression to be taken from the type upon the paper. In this opera- 90 tion the rollers D facilitate the movement of the press.

A proof-press thus constructed can be afforded at a low price to the consumer, and, as it can be used to take a proof from a form se- 95 cured either in a chase or upon a galley, will be found exceedingly useful to the printer.

Having now set forth my invention, what I claim as new is—

In a printer's proof-press, the combination 100

of the following elements: a frame, A, provided with a handle, B, and sides C, having the rollers D, the boxes E, within which are received the circular plates of metal F, having upon one side the eccentric-pins f, and upon the opposite side the crank-arms g, the thumb-screws I, and a roller, G, positioned upon a

shaft, H, constructed and operating substantially as and for the purpose specified.

WILLIAM QUAIL.

In presence of—

WILLIAM V. H. HICKS,
A. SIDNEY DOANE.
